Term of patent 14 years

(Cl. D34—5)

FIG. 1

FIG. 2

FIG.3

FIG. 1 is a front perspective view of a combined desk and bowling score indicator panel showing my new design;

FIG. 2 is a side elevation view thereof; and

FIG. 3 is an enlarged fragmentary perspective view thereof.

The dominant features of my design reside in the portions shown in full lines. The rear and bottom surfaces thereof are each substantially plane.

I claim:

The ornamental design for a combined desk and bowling score indicator panel, as shown and described.
